FOUNTAIN BRUSH

Filed July 29, 1926

By

John Murphy Jr.
Attorney

UNITED STATES PATENT OFFICE.

FRANCIS J. CARBERRY, OF NEW ORLEANS, LOUISIANA.

FOUNTAIN BRUSH.

Application filed July 29, 1926. Serial No. 125,739.

This invention relates to and has for one of its objects to provide a cleaning or painting brush of the fountain type which shall be simple and inexpensive to manufacture and equipped with means by which the flow of cleaning fluid or paint may be accurately controlled.

With the foregoing and other objects in view, the nature of which will become apparent as the description proceeds, the invention consists of the novel construction, combination and arrangement of parts hereinafter fully described and claimed, and illustrated in the accompanying drawing, 15 wherein:

Figure 1 is a sectional view taken on a plane extending longitudinally and centrally through a fountain brush constructed in accordance with my invention, and

Figure 2 is a sectional view taken on the plane indicated by the line 2—2 of Figure 1.

The brush comprises a head 1, bristles 2 and a hollow handle 3. The head 1 may be of any contour, and if desired fibre or hair 25 may be used in place of the bristles 2. The shape of the head 1 and whether bristles, fibre or hair is to be used will depend solely on the nature of the work the brush is designed to perform. The head 1 is provided with a central opening 4 to permit cleaning fluid or paint to be supplied to the bristles 2 by way 30 of the handle 3. A metal jacket 5 which embraces the top and lateral sides of the head 1 and extends into and contacts with the 35 wall of the opening 4, reinforces the head and assists in securing the bristles 2 thereto. A housing 6 is secured to the forward end of the handle 3 and has a snug fit with the head 1. The head 1 and housing 6 are 40 secured together by a screw 7, and the latter is provided with a central tube 8 which fits in the opening 4 and has a snug contact with that portion of the jacket 5 located within the opening. A tube 9 is located 45 within the handle 3, and has its rearward end enlarged to provide a valve casing 10. A partition 11 located within the handle 3 and having the forward end of the tube 9 secured thereto, and the valve casing 10, 50 supports the tube centrally within the handle and provides means through the medium of which the tube may be secured in the handle against endwise movement with respect thereto. At its point of communication with the tube 9, 55 the valve casing 10 is formed to provide a conical valve seat 12 with which the forward

end of a hollow cylindrical valve 13 cooperates to regulate the flow of cleaning fluid or paint to the bristles 2. The valve 13 is provided in its lateral side and adjacent its forward end with outlet openings 14, and its rearward end is enlarged as shown at 15 and internally threaded to permit a hose extending from a suitable source of cleaning fluid or paint, to be coupled thereto. The coupling end 15 of the valve 13 carries a screen 16 which is secured in place by a ring 17 and functions to prevent solid particles from reaching the bristles 2. The valve casing 10 is interiorly enlarged between its ends as 70 shown at 18, and the valve 13 passes through and has threaded engagement with said enlarged portion. A packing member 19 having threaded engagement with the rearward end of the valve casing 10 and snugly contacting with the valve 13, together with the screw threaded connection between the valve and casing, prevents the cleaning fluid or paint from leaking out through the rearward end of the handle 3.

From the foregoing description, taken in connection with the accompanying drawing, it should be understood that while the head 1 and handle 3 are firmly connected together they may be readily separated when occasion demands, and that to permit the cleaning fluid or paint to flow to the bristles 2, it is only necessary to turn the valve 13 backward. This movement thereof carries the forward end of the valve 13 away from its seat 12. 90 Whenever it is desired to cut off the flow of cleaning fluid or paint, it is only necessary to seat the valve 13, and by adjusting the valve with respect to its seat 12, the volume of cleaning fluid or paint flowing to the bristles 95 2 will be regulated and controlled. The valve 13 may be readily adjusted through the medium of its coupling end 15, and a hose or flexible tube extending from a source of cleaning fluid or paint under pressure, can be readily connected to the valve through the medium of said end thereof.

It should be understood that the drawing is merely illustrative and does not pretend to give exact proportions. Furthermore the 105 said drawing is illustrative of a preferred construction, it being my expectation that various changes and modifications may be made without departing from the spirit and scope of my invention.

What is claimed is:—

A fountain brush comprising a head pro-

vided with an opening and with bristles or the like, a jacket secured to the head and snugly contacting with the top, the wall of the opening and lateral sides of the head and adapted to aid in securing the bristles thereto, a housing mounted on said head and jacket and including a top wall having an opening alining with the opening in the head, a circumferential flange on said housing em-

bracing the head and jacket, an interior 10 flange snugly fitting the opening in the head, a hollow handle supported by said housing and communicating with the opening in the housing, and a coupling member carried by the handle. 15

In testimony whereof I affix my signature.

FRANCIS J. CARBERRY.
